(57) **CLAIM**

The ornamental design for a wheeled chair and walker combination as shown and described.

DESCRIPTION

2. Wheeled chair and walker combination

FIG. 2.1 is a perspective front view in a first state;

FIG. 2.2 is a left side view in a first state;

FIG. 2.3 is a perspective front view in a second state;

FIG. 2.4 is a left side view in a second state;

FIG. 2.5 is a perspective front view in a third state;

FIG. 2.6 is a left side view in a third state;

FIG. 2.7 is a left side view in a fourth state;

FIG. 2.8 is a perspective front view in a fourth state;

FIG. 2.9 is a top view in a first state;

FIG. 2.10 is a top view in a second state;

FIG. 2.11 is a top view in a third state;

FIG. 2.12 is a top view in a fourth state;

FIG. 2.13 is a perspective back view in a first state;

FIG. 2.14 is a front view in a first state;

FIG. 2.15 is a back view in a first state;

FIG. 2.16 is a right side view in a first state;

FIG. 2.17 is a bottom view in a first state;

FIG. 2.18 is a perspective back view in a second state;

FIG. 2.19 is a front view in a second state;

FIG. 2.20 is a back view in a second state;

(Continued)

FIG. 2.21 is a right side view in a second state;
 FIG. 2.22 is a bottom view in a second state;
 FIG. 2.23 is a perspective back view in a third state;
 FIG. 2.24 is a front view in a third state;
 FIG. 2.25 is a back view in a third state;
 FIG. 2.26 is a right side view in a third state;
 FIG. 2.27 is a bottom view in a third state;
 FIG. 2.28 is a perspective back view in a fourth state;
 FIG. 2.29 is a front view in a fourth state;
 FIG. 2.30 is a back view in a fourth state;
 FIG. 2.31 is a right side view in a fourth state;
 FIG. 2.32 is a bottom view in a fourth state.
